UNITED STATES PATENT OFFICE.

WILLIAM H. CORE, OF NEW YORK, N. Y.

DESIGN FOR A SHOW-CASE.

Specification forming part of Design No. 5,128, dated July 18, 1871.

To all whom it may concern:

Be it known that I, WILLIAM H. CORE, of the city of New York, in the county and State of New York, have invented a new and original Design for a Show-Case; and I do hereby declare that the following is a full, clear, and exact description thereof, which will enable others skilled in the art to make and use the same, reference being had to the accompanying drawing forming part of this specification.

My improved design for a show-case consists

in forming it with a top curved from the back or a point near the back to 'a, where it is joined to or meets the front 'c, which is vertical or nearly so.

I claim as my invention—

The design for a show-case, as set forth.

The above specification of my invention signed by me this 14th day of June, 1871.

W. H. CORE.
